CASE

George Rosenberg, New Rochelle, N. Y.

Application June 17, 1938, Serial No. 214,190

3 Claims. (Cl. 150—28)

This invention relates to cases or containers, more especially for personal use, as for a cigarette case, lady's handbag, or like.

The primary object of my invention is to generally improve cases of this character, and more particularly cases made almost wholly of a flexible material such as leather, imitation leather, fabric, or the like. A more particular object resides in the provision of such a case which will hold its shape well over long-continued use.

Other objects of my invention are to simplify the assembly of the case; to cheapen the cost of manufacture of the same; to improve the appearance of the case by the addition of simulated ornamental metallic edges; and to utilize these metallic edges not merely as ornamentation, but also as important structural parts of the case for holding the parts of the same in desired relation. Ornamental metallic corners or beads are frequently employed solely for ornamentation, but often become loose and fall off, and considered in this aspect, an object of the present invention is to so secure ornamental metallic beads to the case that they cannot fall off.

Further objects are to minimize the number of parts required and the number of operations needed to make and assemble the case; to provide a lining for the exterior material of the case with a minimum of labor and expense; and to provide a readily openable closure and means to hold the same in normally closed position, all without appreciably complicating the structure of the case. Still another object is to devise a cigarette case embodying the features and advantages of the invention, and in this connection one object of the invention is to so design the cigarette case that it will effectively protect the cigarettes against damage even though the case is made almost wholly of flexible material.

To the accomplishment of the foregoing and such other objects as will hereinafter appear, my invention consists in the flexible and rigid metal elements of the case and their relation one to the other, as hereinafter are more particularly described in the specification and sought to be defined in the claims. The specification is accompanied by a drawing, in which:

Fig. 1 is a front elevation of a cigarette case with the closure flap in open condition to expose the cigarettes;

Fig. 2 is an end elevation of the case with the flap in closed position;

Fig. 3 is a perspective view explanatory of the construction of the ends of the case;

Fig. 4 shows the laminated assembly of exterior

and lining materials prior to assembly with the ends of the case;

Fig. 5 is an enlarged section through one edge of the laminated assembly of Fig. 4;

Fig. 6 is a similar view explanatory of a modification;

Fig. 7 is a horizontal section through the end of the case prior to closing the metal channels;

Fig. 8 is a similar view subsequent to closing the channels;

Fig. 9 is a section through the strap of the case;

Fig. 10 is a section through the edge of the flap of the case;

Fig. 11 is a section in the plane of the line 11—11 of Fig. 4; and

Fig. 12 is a vertical section explanatory of a modification of the invention.

While the invention is disclosed as applied to a cigarette case, it will be understood that this is by way of exemplification rather than limitation of the invention, and the features of the invention are applicable to other types of case.

Referring to the drawing, and more particularly to Figs. 1 and 2, the cigarette case comprises spaced front and back walls 12 and 14 made of a suitable flexible material such as leather, imitation leather, fabric or the like. These walls are held apart in desired spaced relation by rigid metallic end walls 16. The end walls, however, are preferably made to closely simulate gussets of the conventional stitched type, and to this end the metal walls are curved somewhat in section, being convex inwardly, as is best shown in Figs. 7 and 8. Even more important, the center portion or area of the end walls is covered with a flexible material which may differ from, but preferably is, the same material as the exterior or covering material of the case.

The edge portions of the end walls are bent outwardly at 18 and are then reversely bent or curled as is indicated at 20, thereby forming metal channels which receive the edges of the front and back walls 12 and 14 of the case. These channels may be closed and clamped tightly against the edges of the front and back walls, as is shown in Fig. 8, thereby locking the parts in assembled relation. Thus the end walls function not only as end walls, but also as rigid spacing means for holding the front and back walls in desired spaced relation. The metallic end walls insure that the case will be maintained in shape over long use. The exposed edge portions or channel portions of the end walls do not detract from the appearance of the case, but on the contrary, may be, and preferably are, given a high polish and a finish

simulating precious metal. They then form a distinct color contrast with the exterior material of the case and appear to be ornamental beading or edging applied to the ends of the case solely for ornamental purposes and to enrich the appearance of the case.

Considering the arrangement in greater detail, the case further comprises a bottom wall 22 and a closure flap 24 which are preferably made integral with the front and back walls 12 and 14. Bottom wall 22 connects the front and back wall, while the closure flap 24 is an extension of the back wall. The closure flap may be held in normally closed position by inserting the flap beneath a strap 26 extending across the front of the case from side edge to side edge, as is indicated in Fig. 2, and also indicated by the broken line position 24' of the flap in Fig. 1.

Referring to Fig. 4, all of the walls of the case except for the end walls, are made out of a single piece of covering material. The case is preferably lined with a suitable lining material such as silk fabric. For this purpose a piece of the lining material is cut out which is substantially coextensive in area with the covering material except for a small amount of marginal material used as an edge finish or hem 28. The exterior and lining materials are stitched together by a peripheral line of stitching 30. This also holds the hem. The construction will be evident from Fig. 5, in which the leather or other exterior covering material is indicated at 32 while the lining material is indicated at 34. The edge portion 28 of the covering material is folded over onto the lining material 34 and stitched in place by the peripheral line of stitching indicated by the dotted line 30 in Fig. 4. It will be understood that the laminations may be secured together in better fashion for a higher-priced article, though at greater expense, and this is indicated in Fig. 6, in which it will be seen that the covering material 36 and lining material 38 are both folded inwardly and stitched together, resulting in a stiffened and finished edge 45 with no exposed hem. Any such form of edge finish may be employed with the present invention.

The bottom edge of the blank shown in Fig. 4 is cut away at the bottom, as is indicated at 40, this corresponding to the dropped edge or recess 40 clearly shown in Fig. 1. It will be understood that this feature is of particular advantage in connection with a cigarette case because it facilitates removal of the cigarettes. If the closure 55 is to be held in place by means of a strap such as the strap 26 of Figs. 1 and 2, this strap is preferably preliminarily secured to the blank while the latter is still in flat condition. This is indicated at 26 in Fig. 4, and the regular 60 line of peripheral stitching 30 may be used to hold the ends of strap 26 in place. It will be understood that the strap is secured solely at its ends, the lines of stitching 42 in Fig. 1 functioning merely to secure the folded edges of the 65 strap in position, as is best shown in Fig. 10 of the drawing.

To carry out the decorative scheme of the case, the edge of flap 24 may have applied thereto an ornamental bead or channel 44, this being 70 made with the same metal finish as the end channels, that is, simulated gold, silver, chromium, or the like. It is also made similar in dimension, thus carrying out the illusion that all of the exposed metal edges consist of such 75 ornamental channels. The part 44 is applied

over the edge of flap 24 in a manner which will be clear from inspection of Fig. 10, the metal sides of the channel simply being clamped or closed together to secure the channel to the flap. It will be understood that the part 44 may be applied to the flap either before or after assembling the parts of the case together.

The construction of the metallic ends of the case is probably already understood. A word may be said, however, concerning the method of adding the covering material 46 to the ends. Strips of the covering material may be cemented directly to the metal. However, it is difficult to obtain an absolutely dependable union between the leather and metal, and moreover, it is desirable to fold the covering material inwardly about the upper edge of the metal end or gusset. I therefore recommend that a covering strip more than twice the length of the end be used, and this is folded about the metal, until the ends of the covering strip overlap, as is clearly shown at 48 in Fig. 3. The ends are cemented together, and an excellent bond is obtained. If desired, the covering material may be additionally cemented to the metal, but this is not essential. This method of applying the covering material has the further advantage that the inside of the case is devoid of exposed metal. In fact, the illusion of a leather wall with metal corner strips is so good that the detection of the metal end walls can be made only by destroying a part of the case.

It will be understood, however, that while I recommend covering of the end walls to simulate an all-leather case, it is possible to leave the end walls exposed, thus relying on contrast between the metal and covering material over the entire area of the end walls.

To assemble the three main parts of the case, it is merely necessary to fold the blank of Fig. 4 on fold lines 58 and 52 until the front and back walls 12 and 14 come into spaced parallel relation. A preliminarily covered end wall is then slipped over the edges of the front and back walls, and the assembly is placed in a suitable die which is then actuated to close the channels, thus changing the parts from the condition shown in Fig. 7 to that shown in Fig. 8, and thereby securely locking the parts in assembled relation. The opposite end wall is applied in similar fashion. The labor for completing the 50 case is thus minimized, for upon addition of the end walls the case is a finished article ready for use. The operation of adding the end walls of the present case is to be contrasted with the difficult operation of stitching leather gussets in 55 place, for it is not possible to stitch such gussets on an ordinary sewing machine, and they must instead be stitched on a raised machine provided with a horn or rest of special character.

The closure is formed by simply bending the blank of Fig. 4 on the fold lines 54 and 56. The case is held in desired shape because of the stiffening influence of the metallic end walls. If desired, the flexible walls may themselves be stiffened somewhat by the use of paper or cardboard or fibre inserts or fillers between the lining and covering material. This expedient is frequently resorted to when using imitation leather which is thin and more flexible than real leather would be. If such inserts are used, they are preferably omitted at the fold lines of the blank. Thus, referring to Figs. 4 and 11, the flap 24 is stiffened by an insert 60; the top edge of the closure is stiffened by a narrow insert 62; and the bottom 22 75

is stiffened by a similar narrow insert 64. If desired, the front and back walls 16 may themselves be stiffened by inserts 60 and 68 respectively, but these are not nearly as important or as necessary as the inserts 60, 62 and 64. The inserts 62 and 64 strengthen the case and protect the cigarettes against flattening of the case at the middle, where the protection afforded by the metallic ends is least felt, while the insert 60 adds body to the flap and prevents curling thereof at the end. An appreciable space, say $\frac{1}{8}$ of an inch, is left between the inserts at the fold lines 50, 52, 54 and 56, thus maintaining the desired maximum flexibility at these points.

The invention is not limited to a cigarette case, and may be applied to cases intended for a variety of special purposes, as for example, a mani-curing set, a safety razor kit, or in somewhat larger size, as a lady's handbag. For the latter, purpose, the distance between the front and rear walls may be substantial, say, $1\frac{1}{2}$ or 2 inches. The metallic end walls are readily increased to the desired width. However, some difficulty may arise due to a slight sagging of the bottom wall 22 away from the lower extremities of the metal walls. The possibility of escape of tiny articles, coins or the like, at these lower corners may be avoided by providing upwardly turned flaps or angle pieces for the corners. Referring to Fig. 4, the piece 76 may be formed integrally with the main blank, it projecting outwardly at the part corresponding to the bottom wall 22. However, in order to avoid excessive waste of material, the part 70 is preferably formed out of a separate piece of material stitched to the blank, as is indicated at the other side of the blank shown in Fig. 4. Thus the part 72 is an outward extension of an inner part 74 which is stitched to the blank by a rectangular line of stitching 76.

It will be understood that when the ends are being assembled to the flexible walls of the case, the parts 70 or 72 are turned upwardly inside the end walls, as is best shown in Fig. 12. If desired, the upwardly turned part may be cemented to the inside of the end wall, thus preventing it from being turned down away from the end wall during use of the case.

In respect to the stiffening or filling pieces, it may be mentioned that the stiff, narrow pieces 62 and 64 are preferably held in position by being cemented on both sides, that is, to both the exterior covering material of the case and the inner lining material. The insert or stiffening piece 60 is preferably cemented on only one side, that is, to the exterior of the case, so that the silk or other lining will be somewhat movable and feel and act as a free lining. The reason the narrow inserts 62 and 64 are preferably cemented to the lining as well as the leather or outside material is to prevent the lining from bulging inwardly excessively due to the folds 54 and 56 being located so closely together. By cementing the lining material to the strip 62, for example, the loose lining material at the actual fold lines 54 and 56 is kept neatly confined to the actual location of the fold or bend.

It is believed that the construction and the method of manufacture and assembly of my improved case, as well as the many advantages thereof, will be apparent from the foregoing description. The case is of the soft type, being made almost wholly of flexible material, yet it holds its shape even after long-continued use.

The case is made of a minimum number of parts and is assembled with a minimum amount of labor. It is not only inexpensive to manufacture and assemble, but the appearance of the case is greatly improved and enriched by the exposed metallic edges or beads which appear to be applied solely for ornamentation, although actually fulfilling important functions heretofore described. The exposed metal beads, if considered solely as ornamentation, have the important advantage of being securely applied, for they are integral with the ends of the case.

It will be apparent that while I have shown and described my invention in a preferred form, many changes and modifications may be made in the structure disclosed without departing from the spirit of the invention defined in the following claims.

I claim:

1. A case comprising front and back walls connected by a bottom wall, end walls securing said front and back walls in spaced parallel relation, said walls other than the end walls being made of flexible material and said end walls being made of metal, said end walls having channels at the side edges only and receiving the edges of the front and back walls, and flexible material covering the outer faces of the end walls except for the channel portions, the lower portions of said flexible material folded about the lower edges of the end walls and secured to the inside of the case, whereby the channel portions alone are exposed to simulate ornamental metallic beads applied to the corners of a flexible case.

2. A case comprising front and back walls connected by a bottom wall, a closure flap extending from the back wall, means on the front wall for holding the closure flap in closed position, end walls securing said front and back walls in spaced parallel relation, said walls other than the end walls being made of flexible material and said end walls being made of metal, said end walls having channels at the side edges only and receiving the edges of the front and back walls, flexible material covering the outer faces of the end walls except for the channel portions, the lower portions of said flexible material folded about the lower edges of the end walls and secured to the inside of the case, whereby the channel portions alone are exposed to simulate ornamental metallic beads applied to the corners of a flexible case, and the free end of the closure flap being provided with an ornamental metallic bead clamped thereon to heighten the illusion of the corners being mere ornamental beads.

3. A case comprising front and back walls connected by a bottom wall, said walls being made of flexible material, a piece of lining material secured to the inner face of said walls to form a laminated structure, a strip of stiffening material disposed between the lamination at the bottom wall, metallic end walls securing said front and back walls in spaced parallel relation, said end walls having channels at the side edges only and receiving the edges of the front and back walls, and flexible material covering the outer faces of the end walls except for the channel portions, the lower portions of said flexible material folded about the lower edges of the end walls and secured to the inside of the case, whereby the channel portions alone are exposed to simulate ornamental metallic beads applied to the corners of a flexible case.

GEORGE ROSENBERG.
